CARRYING CASE FOR MAGNETIC RECORDER-REPRODUCER

Sheldon Lee Pastor, Chicago, and Eugene R. Russell,
Barrington, Ill., assignors to Revere Camera Company,
Chicago, Ill., a corporation of Delaware

Application February 7, 1955, Serial No. 34,397

Term of patent 14 years

(Cl. D26—14)

Fig. 1

Fig. 1 of the drawings is a perspective view looking from above toward the front and one side of a carrying case for a magnetic recorder-reproducer showing our new design;

Fig. 2 is a perspective view of the carrying case looking from above toward the back and the other side, and

Fig. 3 is a perspective view of the carrying case looking from below toward the front.

The characteristic features of our design for the carrying case for magnetic recorder-reproducer disclosed reside in the handle and lock member on the front and the vertical and horizontal strips on the rear, having the configurations and arrangements shown.

We claim:

The ornamental design for a carrying case for magnetic recorder-reproducer, as shown and described.
